UNITED STATES PATENT OFFICE.

MARTIN LANDENBERGER, JR., OF PHILADELPHIA, PENNSYLVANIA.

DESIGN FOR A CAPE.

Specification forming part of Design No. 6,629, dated May 6, 1873; application filed April 8, 1873.

To all whom it may concern:

Be it known that I, MARTIN LANDENBERGER, Jr., of Philadelphia, Pennsylvania, have invented a Design for a Garment, of which the following is a specification:

In the accompanying drawing, Figure 1 represents a perspective view of a circular garment made in accordance with my design as it appears upon the wearer, and Fig. 2 is an enlarged view of the fringe with which the said garment is ornamented.

The garment is of the usual shape, and is provided with a hood, A, ornamented by a row of buttons and by a bow, a, having long pendent ends, as shown. The main feature of the design, however, is the deep fringe B, which forms a border for both the body of the garment and the hood. This fringe, as will be best observed in the enlarged view, Fig. 2,

consists of a closely-united gimp-like portion, x, from which hang long crimped threads y, the latter, in the present instance, being of two shades or colors so as to present the appearance of stripes.

Irrespective of the colors employed, I claim—

1. The design for a circular garment ornamented by a deep crimped fringe, B, of the character shown and described.

2. The design for the whole garment, substantially as described, and as represented in and by the accompanying drawing.

In testimony whereof I have signed my name to this specification in the presence of two subscribing witnesses.

MARTIN LANDENBERGER, JR.
